[57] CLAIM

The ornamental design for a freewheel body for a freehub, as shown and described.

DESCRIPTION

FIG. 1 is front view of a freewheel body for a freehub showing my new design, shown attached to a freehub in its position of use;

FIG. 2 is an enlarged side elevational view of a freewheel body for a freehub, it being understood that the opposite side is a mirror image thereof;

FIG. 3 is an enlarged top plan view thereof; and,
FIG. 4 is an enlarged perspective view thereof.

The bottom of the freewheel body for a freehub is plain and unornamented.

The broken line showing of environment is for illustrative purposes only and forms no part of the claimed design.
